GAS MASK CANISTER

William E. Gross, Joppa, Md.

Application February 4, 1942, Serial No. 429,495

8 Claims. (Cl. 183—44)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates generally to protective equipment, and particularly to apparatus for the protection of non-combatants against noxious and deleterious gases, fumes, vapors, etc.

In order to render air contaminated with gases and smokes fit for breathing, it has been and now is the practice to use a gas mask having a canister associated therewith, whereby all inhaled air must first pass through the canister wherein it is filtered and purified.

For maximum efficiency and effectiveness, the canister must be reliable in its action and capable of delivering to the user substantially pure air; it should be compact and light in weight so as not to tire the wearer; and it must be cheap to manufacture, durable, convenient to carry, and quickly adjustable to operating condition.

It is, therefore, generally an object of this invention to provide a canister possessing to as high a degree as possible, all the qualifications above enumerated.

One of the specific objects of the invention is to materially improve upon the manner of assembling the several elements of the canister to the end that soldering of parts together, as a step in the assembling method, is eliminated.

Another specific object is to improve upon the relative arrangement of the several elements, whereby, without any decrease in the ability of the canister to deliver substantially pure air to the user, resistance to breathing is reduced to a minimum.

A further specific object of the invention is to provide against radial and longitudinal shifting of the chemical container within the casing of the canister.

An additional specific object is to improve materially upon the manner and method of assembling the nozzle to the top of the canister casing.

The invention, together with the enumerated and other objects thereof, will be best understood from a study of the following description, taken in connection with the accompanying drawing, wherein:

Figure 1 is a vertical section through a gas mask canister embodying the features of this invention.

Figure 2 is a horizontal section, taken substantially on line 2—2 of Figure 1; and

Figure 3 is a bottom plan view.

Referring now in detail to the drawing, it will 55 of the central breathing tube 10. Tube 10 is

2

be seen that essentially the canister comprises an outer casing 5, provided with an inhalation valve 6 mounted on the bottom wall thereof, and a nozzle 7 projecting from the top wall thereof; an internal chemical container 8 upon which is circumferentially disposed a smoke filter 9; and a central breathing tube 10 in alignment and communication with the nozzle 7 and having associated therewith a dust bag 11.

The canister so generally described is commonly known as a central breathing tube canister, and in the present instance the casing 5 thereof is waterproof, is formed preferably from metal, and is generally tubular or cylindrical in cross section.

The casing 5 embodies a bottom plate 12 and a top plate 13, respectively, in accordance with this invention, crimped into tight engagement with the peripheral wall of the canister casing. By so fastening or jointing the referred to walls of the casing, the use of solder is avoided.

The internal container 8 serves as a receptacle for granular or powdered chemicals 14, the function of which is to purify air passing therethrough. In accordance with my invention, I have from the standpoint of assembly, preferably constructed this container of separable walls, including the perforated peripheral wall 15, bottom wall 16, and top wall 17. Walls 16, 17 fit snugly with the confines of peripheral wall 15, and, respectively, have peripheral flanges 18, 19, respectively, crimped over the extremities of the peripheral wall 15 as shown to provide airtight, leak-proof joints between the walls, without recourse to soldering these joints.

A further advantage over known methods of sealing the joints between the indicated walls of the chemical container is that by so crimping the flanges 18, 19 into engagement with the peripheral wall 15, but a single operation is required to effect the forming of these joints and the securing of the smoke filter 9 in encompassing position on the chemical container. In this connection, it may be noted that the filter 9 is preferably in the form of a paper strip, suitably treated for the purpose, and given several turns about the container wall. The upper and lower edges of this wrapped filter are secured by the crimped edges of the top and bottom wall flanges 18, 19, as shown for positively securing the smoke filter 9 in position.

The walls 16, 17 of the chemical container have the central portions thereof dished as at 20, 21 to receive the lower and upper ends respectively

formed of perforated metal and is open at its respective opposite ends. The lower end of this tube is closed by the wall 16, while the upper end thereof is in substantial registry with an opening 22 formed in the dished central portion 21 of wall 17, and accommodates the inner end of a nipple 31 as shown in Figure 1. Walls 16, 17, thus serve to retain the breathing tube 10 in proper position within the canister.

Among the salient features of this invention is the position of the dust bag 11 relative to the central breathing tube 10. Heretofore, it has always been the practice to sleeve this bag onto the tube, thereby positioning the former exteriorly of the latter. The main difficulty attending the having of the dust bag on the outside of the tube is the increase of resistance to breathing resulting from the bag being compressed against the tube by the chemicals 14 in the container 8.

It may perhaps appear to be an obvious expedient to locate the dust bag as now proposed, within the breathing tube to avoid the difficulty above noted with reference to the usual practice. However, it must be borne in mind that one of the essential functions of this dust bag is to substantially seal the breathing tube against the entrance of the granular chemicals thereto. The problem then to be solved for advantageously placing the dust bag interiorly of the tube was to preserve this sealing effect of the bag. This problem was partially solved by providing the aforementioned dished central portions in the top and bottom walls 17, 16 of the chemical container. Yet there remained the necessity of securing the bag taut if the desired low resistance to breathing was to be had.

I have found that without materially adding to cost or difficulty of assembly, the desired efficacy of the bag was not only preserved but greatly enhanced by forming the bag into an open-end tube exceeding in length the length of the breathing tube. Upon locating the bag within the tube, the surplus or extended ends thereof are turned back over the extremities of the tube and to the outer side thereof. Next, tight-fitting caps 24, 25 are telescopically fitted over the ends of the breathing tube and serve to secure the ends of the bag in position, that is, with the bag in the taut condition lining the breathing tube as shown.

Thus the dust bag is held against being compressed against the wall of the tube and adversely affecting breathing resistance. At the same time, the tube is effectively sealed against the entrance of any granules of the chemical purifying agent 14. Moreover, it is not necessary to solder the caps in place, and the caps function as baffles so that the purified air must pass through the perforations in the area of the wall of the breathing tube that is exposed between the confronting ends of the skirt portions of the caps.

Another salient feature of this invention is the securing of the chemical container against radial and longitudinal movement or displacement within the casing of the canister. To that end I provide a frusto-conical member 26 of very light metal and perforated as shown so as not to offer any material resistance to the flow of air through the canister.

The member 26 is disposed within the bottom portion of the casing 5, and has its base edge resting on the bottom plate 12 at the joint between said bottom wall and the peripheral wall of the

casing. At its apex, the conical support 26 is provided with an opening in which is snugly fitted the dished central portion 20 of the container wall 16. Consequently, container 8 at the bottom thereof seats on the member 26 to be held thereby against radial movement, and with the crimped joint between walls 15 and 17 held seated in a circular groove 27 provided on the inner or under face of the top plate 13 of outer casing 5 to secure the chemical container against longitudinal displacement within the canister casing.

The bottom plate 12 of the canister casing 5 has an opening therein in which is positioned the inlet valve 6 comprising a plate 28 having openings 29 therein for the passage of inspired air, and a rubber flap valve disc 30 for normally closing these openings and secured to plate 28 by a central rivet 31.

20 The path of air or gases entering and leaving the canister is indicated by arrows. The air or gas mixture enters by way of the just described inlet valve and passes through the perforations in support 26, then successively through the filter 9 which serves to remove the smoke particles, the chemicals 14, such as activated charcoal and soda lime, which cleanse the air of injurious gases, and the dust bag 10 which is preferably of thin dust filtering material; the purified air 25 leaving the canister through the breathing tube 10 and nozzle 7.

The nozzle 7, in accordance with this invention, is advantageously secured to the top 13 of the canister casing 5 by dip soldering. This is 30 made possible by recourse to the nipple 31 that is fitted in a flanged opening 32 in the casing top 13 and an opening 33 formed in the dished central portion 21 of the top wall 17 of the chemical container, and which is in registry with opening 32.

Nipple 31 at its inner end is swaged to the chemical container wall 17 as at 34, 34. The nozzle 7 is sleeved onto the flange 35 rimming the aforementioned opening in the canister wall 45 13, and is soldered to the upper edge of said flange all around to provide an air-tight joint therebetween. The nipple 31 is then spot soldered to the nozzle 7 at preferably three points spaced circumferentially of the nipple.

50 A canister embodying the herein disclosed features, in addition to being thoroughly reliable in delivering to the user substantially pure air is light in weight and quickly attachable to the face piece of the gas mask. And while particularly 55 adapted for use in association with face pieces for providing gas masks found most suitable for non-combatants, particularly women and children, the canister of this invention is not limited to such use, but may be employed to advantage wherever the need of such might exist.

It is also to be understood that the herein shown and described preferred embodiment of the invention should be construed as illustrative and not by way of limitation, since many variations 60 will occur to those skilled in the art and within the scope of the appended claims.

I claim:

1. A canister for gas masks comprising an outer casing having an air inlet and an air outlet, air filtering and purifying means within the casing and embodying a container, a breathing tube disposed within said container and in communication with the air outlet, granular air-purifying material around said tube, a dust bag lining inside said breathing tube and having open end

portions sleeved on the tube at the respective opposite ends of the latter, and cap elements fitted on said ends of the breathing tube.

2. A canister for gas masks comprising an outer casing having an air inlet and an air outlet, air filtering and purifying means within the casing and embodying a peripheral wall, a top wall, and a bottom wall, said top wall and said bottom wall, respectively, having a dished central portion, said top wall having an opening in the dished portion thereof and in registry with the air outlet, a breathing tube having open ends disposed in the dished portions of said top and bottom walls, granular air-purifying material around said tube and a dust bag lining inside the breathing tube and having exposed ends sleeved on the tube at the said open ends of the tube.

3. A gas mask canister comprising an outer casing having an air inlet and an air outlet; air filtering and purifying means within the casing and embodying a container having a peripheral wall, a bottom wall, and a top wall, said bottom wall and said top wall respectively, having a central dished portion, the top wall having also an opening in the dished portion thereof in registry with said air outlet; a breathing tube having open ends disposed in the dished portions of said top and bottom walls; a dust bag, tubular in form and open at its ends, having an intermediate portion within the breathing tube and externally disposed end portions sleeved on the tube at the ends of the latter; and caps telescopied on said ends of the tube and embracing said ends of the dust bag, the cap on the upper end of said tube having an opening therein affording direct communication between the tube and air outlet.

4. A canister for gas masks comprising an outer casing having an air inlet and an air outlet, a chemical container within said casing, granular air purifying material in said container, a breathing tube disposed within the container and in communication with said air outlet, and a dust bag lining said breathing tube and protected by said tube against pressure-exerting contact of the granular contents of the container therewith, whereby the low breathing resistance of the dust bag is maintained.

5. An outer casing for gas mask canisters having a wall provided therein with an opening and

a flange rimming said opening, a nipple disposed in the opening and having an end projected beyond the flange, and a nozzle sleeved on the flange; said nozzle being soldered to the outer edge of the flange to provide an air-tight joint therebetween, and also being spot soldered to said end of the nipple at circumferentially spaced points.

10 5. A gas mask canister having an outer casing provided with a wall having an opening therein, an inner container having a wall in spaced opposed relation to the mentioned wall of the outer casing and provided with an opening in registry with the first mentioned opening, and a nozzle accommodating nipple fitted in the registering openings and having an inner end portion swaged onto the mentioned wall of the inner container.

15 6. In an air purifying canister, an outer casing having a wall provided therein with an opening, a flange on the wall and rimming the opening, air filtering and purifying means within the casing and including a container having a wall provided with an opening in registry with the first mentioned opening, a nipple having one end thereof projected through the opening in the outer casing wall beyond the flange, and an opposite end extended into said container and swaged to the mentioned wall of said container about the opening therein, and a nozzle sleeved on said flange and soldered thereto and to the first mentioned end of the nipple.

20 35 7. A canister for gas masks comprising an outer casing having an air inlet at a bottom part and an air outlet at a top part thereof, within the casing a chemical container having a filling of a granular air-purifying material and a bottom wall, a breathing tube having a thin dust-filtering lining centrally disposed within the container, said breathing tube being in communication with the air outlet at its upper end and extending to the bottom of the chemical container where it has a closed lower end fixed in place, and a support interposed between the bottom of the casing and the bottom of the chemical container restraining the latter against casual longitudinal and radial displacement within the casing while allowing air to flow from the inlet into the chemical container.

40 45 WILLIAM E. GROSS.
